Primary Examiner — Marie D. Fast Horse*Assistant Examiner* — Jennifer Sierra Yosinski(57) **CLAIM**

The ornamental design for a caddy, as shown and described.

DESCRIPTION

FIG. 1 is a front perspective view showing a new design for a caddy;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the caddy depicted in broken lines in FIGS. 3, 4, 5, and 7 form no part of the claimed design.

1 Claim, 6 Drawing Sheets(56)
